UNITED STATES PATENT OFFICE

HYMAN ELI GOLBER, OF CHICAGO, ILLINOIS, ASSIGNOR TO THE MIEHLE PRINTING PRESS & MANUFACTURING COMPANY, A CORPORATION OF ILLINOIS

PLATE HOOK

Application filed October 15, 1927. Serial No. 226,302.

This invention relates to improvements in printing plate securing means, generally known in the printing trade as plate hooks, and more particularly used for positioning an 5 electrotype or any other printing plate on a supporting base, and securing its rigidly thereto.

Some of the principal objects of my invention are: to provide a plate hook of minimum 10 length in order to be particularly adapted for use in connection with curved supporting bases; to provide means whereby the plate hook is advanced per revolution of its propelling means much slower than has heretofore 15 been known, to make possible exceptional convenient and accurate registering of printing plates; to introduce means whereby the hook is rendered selflocking; and, to provide a durable and compact construction which is 20 simple and efficient in its operation.

Other features and objects of my invention will be apparent from the following description and appended claims.

The improved plate hook is illustrated by 25 three sheets of drawings, in which:

Figure 1 is an end view of the plate hook locked within a groove formed in the surface of a base;

Figure 2 is a view at right angles to that 30 taken in Figure 1;

Figure 3 is a plan view of Figure 1;

Figure 4 is a sectional view taken through the center of Figure 2;

Figure 5 shows a sectional view of the plate hook and its supporting base taken on a plane 35 along line 5-5 of Figure 1;

Figure 6 is a transverse sectional view of the plate hook taken on a plan along line 6-6 of Figure 2;

Figure 7 illustrates the key by means of which the hook is advanced within a groove in the base;

Figures 8 and 9 are two views of a hook wrench by means of which the hook can be conveniently placed into or removed from a groove in the base;

Figures 10 and 11 show a modified form of a hook wrench which embodies safety means 50 as will be hereinafter explained;

Figure 12 shows a portion of the rack provided within a groove of the base;

Figure 13 shows the original form of a clip whereby a rack is secured to the base;

Figure 14 is a plan view of a groove with 55 a pair of cooperating racks applied thereto and showing the relative position of the rack teeth;

Figures 15, 16, 17 and 18 are different views of the wings by means of which a hook is 60 locked in its operative position within a groove of the base.

Referring now to Figure 1, the supporting member or base 1, which can be made of cast iron or of any other suitable material, is 65 formed with one or more grooves 2, preferably comprising vertical walls 3, recesses 4, inclined portions or recesses 5, and a curved base portion 6. The vertical walls 3 serve the purpose of guiding the hook, not only as it is 70 being inserted and withdrawn from the base, but also longitudinally thereof in its operative positioning and locking movements.

The recesses 4 are provided to receive wing members which project laterally from the 75 hook body to engage said recesses and thereby lock the hook firmly in its operative position within the groove, so that it cannot accidentally become disengaged from the base when the latter is manipulated or when it is 80 in operation on the press. Within each of the inclined recesses 5 there is mounted a rack 7, see Fig. 12. These racks, which are oppositely arranged, are held within said recesses by curved clips or wedges 8. 85

In assembling the racks 7 within the grooves, the racks are first put in place loosely, curved clips 8 are then dropped in between the racks, and driven against the curved base 6 so that the longitudinal edges 90 of the clips will become wedged between the bottom of the groove and the lower edges of the racks, as clearly shown in Figures 1 and 6. The clips 8 are so dimensioned that when they are driven into position the racks will 95 be securely held within the inclined recesses 5.

Preferably the racks are made in sections of approximately 4 inches long, so that in case any part of the rack becomes damaged, 100

the respective section can be readily replaced by driving out the clips 8 which apply to the damaged section, and by inserting a new section and securing it with new clips as just described. Preferably the clips are placed at 5 intervals of approximately two inches.

As shown, the racks 7 are composed of a backing 9, and rectangular teeth 10, separated by spaces 11, preferably of the same width as 10 the teeth; however, any desired proportion may be given to the spaces as compared with the width of the teeth. Inasmuch as these 15 rack teeth have a rectangular base and are free on all sides, the possibility of dust and ink clogging between the teeth, or in the vicinity of the racks, is practically eliminated. As a matter of fact, any accumulation of dirt or dried ink within the spaces of or near the 20 rack will be forced out by the normal operation of the hook as will be explained later.

This is a point of primary importance in the construction of plate hooks because many breakages, which occur in the operation of plate hooks, are principally due to the accumulation or clogging of dust and ink between the cooperating parts of such hooks.

As is clearly shown in Figure 1 for example, the groove 2 in the base is cut sufficiently deep so that when the hook is placed therein, 30 there will be sufficient clearance between the bottom of the hook and the bottom of the groove, i. e., the top of the clip 8, to permit of some accumulation of dust or the like without, however, interfering with the operation 35 of the hook. For the same purpose, the recesses 4 are also cut substantially deeper than is necessary to accommodate the locking members or wings of the hook.

The two racks secured within the same 40 groove are so positioned that the teeth 10 of one rack are located opposite the spaces 11 of the other rack. The purpose of this arrangement will be hereinafter apparent.

I will now describe the construction of the 45 plate hook itself. It comprises a body portion or block 12 which serves as a supporting member for the various parts which constitute the plate hook. Rotatably mounted in the block 12 is a pinion 13, see Figures 4 and 50 6. This pinion has a center portion 14 which forms an 8-toothed worm wheel, and two cylindrical portions 15, which act as journals within the bore of the hook body 12. The pinion is also formed with laterally projecting teeth 16 and 17 which mesh with the rack 55 teeth 10. When the pinion 13 is rotated, the teeth 16 and 17 alternately mesh with the teeth 10 of the two racks 7 and thereby propel the plate hook longitudinally within the 60 groove of the base in a direction depending on the direction in which the pinion is rotated.

The provision of a 2-toothed pinion, such as just described, constitutes a very important 65 feature of my invention. It is a well-

known fact that in the majority of plate hooks on the market at the present time, where pinions and racks are used to propel the hook, the pinions, which usually have about 12 teeth, are of such fine pitch that the teeth are actually too weak and therefore become defective very readily. By reducing the number of pinion teeth to a minimum and thereby correspondingly increasing the dimensions of the teeth, while limiting the space required for the pinion, it is also possible to reduce the over all dimensions of the plate hook itself very considerably and yet provide a pinion, the teeth of which are very much larger and stronger than have heretofore been known in the construction of such devices. It will be readily appreciated that this construction of the pinion permits me to build a plate hook that is unusually short and therefore particularly well 85 adapted for use on curved bases.

It will also be understood that as the hook is moved longitudinally of the groove 2 by rotating the pinion 13, the teeth 16 and 17 will pass in between the rack teeth 10 and thereby remove any dirt or clogged ink that might have accumulated in their path within the groove 2, i. e. in the vicinity of the rack teeth 10.

While I have illustrated one preferred form 95 of rack engaging pinion teeth, I do not wish to limit myself to any specific design or dimensions of such teeth, because teeth of cylindrical or substantially cylindrical shape, or of any shape varying from that shown on the drawings, could be used without departing 100 from the purpose of my invention. Likewise, without decreasing the effect of my improved plate hook, two or more teeth of substantially the same size as those illustrated 105 could be arranged on each side of the rack pinion. This might, of course, necessitate a corresponding modification of the design or dimensions of the rack teeth 10.

The feature of providing a rack pinion limited to a small number of teeth has the added 110 advantage that the hook is rendered selflocking, i. e., it will not slip, and cannot be advanced within the base groove by merely pushing it along, because the friction between the pinion teeth and the rack teeth is such that it will not be overcome by an attempt to advance the hook in this manner.

The significance of this selflocking feature 115 will be fully appreciated when it is explained that after the electrotype or similar plates have been accurately registered and secured to a base, which operation is a matter that requires great care and much attention, it frequently occurs that when a number of impressions have been pulled on the press, the plates have become loose and have moved out of register, simply because the hooks have slipped. That is, the constant pressure and vibration incident to printing has caused the 125 130

hooks to loosen their grip on the plate and thereby permit the latter to shift out of register. To prevent such slipping a number of hooks have been provided with catches and friction springs and other similar devices. In my hook, however, this slipping is eliminated by the proportionately large degree of friction created between the teeth of the pinion and their corresponding rack teeth.

In order to make this more readily understood, I quote the following example in which the dimensions given are those adopted in the practical embodiment of the plate hook illustrated in the drawings. For convenience the pitch of the rack has been made exactly .200" divided into a tooth 10 and space 11 of approximately equal width. A complete rotation of the pinion 13 advances the plate hook by one tooth of the rack. Therefore, imagining the pitch line A of the rack, see Fig. 2, and its cooperating pitch line of the pinion, the circumference of the pitch circle B of the pinion is equal to exactly .200" and therefore the diameter of the pitch circle of the pinion is equal to .200" divided by 3.1416 or about .063". The result is that the frictional, i. e. sliding motion between the pinion teeth 16, and the rack teeth 17, very much exceeds the actual distance through which the plate has been propelled. This function could be readily compared with that of a screw where the extent of its frictional, i. e. sliding motion very considerably exceeds the distance by which the screw has actually been advanced. The operation is therefore accompanied by a considerable amount of friction so that because of this frictional locking effect between the pinion teeth and the rack teeth, it will be utterly impossible to dislodge the hook from its operative position, no matter to how great a stress the hook might be subjected.

To rotate the pinion 13, there is provided a worm 18. This worm is inserted into an appropriately shaped bore 19 provided in the hook body 12. The worm 18 is formed with a square hole 20 to receive a key 22, such as illustrated for example in Figure 7, which key, however, may be of any desired form. The square portion 21 of the key 22 fits snugly within the square hole 20 of the worm and the rotation of the key will cause the rotation of the worm, and therefore advance the hook within the groove of the base. The worm is prevented from rising by its upper face 23 abutting against a ledge 24 of the hook body. The worm is retained within the bore 19 by means of a closing slide 25 which is wedge shaped and is driven into a correspondingly machined portion in the hook body.

Preferably the closing slide 25 has a small bore 26 which serves two purposes, namely, it allows of cleaning out any dried ink or dirt that might accumulate within the bore of the worm and it permits of an easy removal of a

broken key that might become lodged in said bore. It should here be explained that for obvious reasons, the key is purposely so dimensioned that in case too much force is applied thereto, it will break before any part of the plate hook itself can break.

The hook is held in the base groove by means of locking ledges or wings 27 and 28. These wings are retained within grooves of the hook body which grooves are appropriately shaped so as to provide the largest possible supporting surface for the wings.

Referring to Figures 15, 16, 17 and 18, it will be seen that each wing has a straight portion 29 forming one of its sides. This portion 29 preferably extends over the entire length of the block 12 and fits within the recess 4 of the base 1 after the hook has been inserted in the groove. The wings are provided at each end with projections 30 and 31. The projections 30 serve as means whereby the hook wrench or remover, see Figure 8, can engage the wings so as to withdraw them into the body of the hook to be flush with the side walls thereof when the hook is being placed into or removed from the base groove. In order to retain the wings within the hook body and to limit their lateral movement, I preferably provide a recess 32 in one of the end walls of the block 12 and downwardly projecting stops 33 in a closing member 34. The projections 31 at one end of the wings extend into said recess and abut against the walls thereof, while the outward movement of the wings at their other ends is limited by the projections 31 engaging the stops 33.

The inner portion of each wing is curvilinearly shaped to save as much room as possible and to make the wings as strong as possible. Inserted between the wings and the adjacent portion of the hook body are preferably two springs 35 which tend to project the wings beyond the side walls of the block 12.

The jaw member 36 which is provided with a clamping face 37 whereby the electrotype or the like plate is engaged, is preferably mounted in the upper face of the hook body so as to pivot therein. Said jaw member also comprises a turn table section 38 and a conical or bearing section 39 as is clearly shown in Figure 4 of the drawings. The conical portion 39 is supported within a correspondingly milled recess or bearing formed partly within the hook body itself and partly within the slidably arranged closing member 34.

In plate hooks of the type having a pivotally arranged plate engaging jaw, it is of course important that the bearing surface within the hook body for supporting such jaw be made as large as possible. Therefore, in designing my plate hook I made the diameter of the turn table section 38 equivalent to the width of the base groove 2. This

will provide the largest possible bearing surface for the jaw member 36.

After the various parts of the plate hook have been assembled, the closing member 34 is locked in its position preferably by means of a pin 40 driven into a bore which partly extends within the closing member 34 and partly within the hook body itself.

In order to permit of convenient insertion and removal of the hook, I have provided a wrench shown in Figures 8 to 11. This wrench has a body portion 41 and two parallel legs 42. These legs fit over the ends of the hook and by means of the beveled faces 43 formed in the free ends of the legs, the projections 30 of the wings are forced together as the wrench is applied to the hook, thereby moving the wings inwardly so as to be flush with the side walls of the hook body. The hook can then be readily placed in its proper position within the base groove, care being taken of course that the teeth of the pinion will clear the rack teeth. Upon removal of the wrench, the projections 30 will be released and the wings 27 and 28 will enter the recesses 4, and securely lock the hook against any upward movement within the groove.

In order that the hook may be readily disengaged from the wrench when the latter is withdrawn, I provide a pusher member 44 slidably mounted within the body portion 41 of the wrench as indicated in Figures 8 to 11. The outer end of said pusher carries a button 45, while a disc 46 is preferably secured to its inner end. In manipulating the wrench, the operator applies his first and second fingers beneath the two laterally projecting arms 47, or within the recesses 48, if the modified form of wrench illustrated in Figures 10 and 11 is used, while the pusher 44, i. e., the button 45, is operated by the thumb.

The modified wrench shown in Figures 10 and 11 is provided with what I might call a safety means, comprising two inwardly projecting wedge members 49 and 50. When the wrench is applied to the hook for the purpose of inserting it into the groove of the base, these wedges will be located just below the projections 30 of the wings 27 and 28 so that when the wrench is withdrawn, after the hook has been placed into the groove, the wedges will pass between said projections and spread them apart so that the wings will be forced into the recesses 4 and remove out of their path any dirt or the like that might be lodged therein and ordinarily prevent the wings from spreading in order to enter said recesses.

It will be apparent that, with a construction embodying the features of my invention, I provide a plate hook that is exceedingly durable and simple in its operation, occupies a limited amount of space within a groove of a printing plate supporting base and permits

such close approach of the clamping jaw of two opposed hooks, that the smallest possible plate can be very readily secured to such base.

While I have described and illustrated one preferred form of construction, I wish it to be understood that various modifications may be embodied in my plate hook without departing from the spirit of the invention, therefore, it is my intention to cover all such modifications that will come within the scope of the appended claims.

I claim:

1. In printing plate securing means, the combination of a plate supporting base having a groove, a rack arranged on each side wall of said groove and adjacent the bottom thereof, a plate engaging hook including a driven element cooperating with said racks to move said hook longitudinally of said groove, said driven element having a laterally extending tooth at each side to mesh with said racks.

2. In printing plate securing means, the combination of a plate supporting base, having a groove, rack means within said groove, a plate engaging hook including a rack engaging pinion, the diameter of the pitch circle of the teeth on said pinion being less than one-half of the diameter of the pinion.

3. A printing plate supporting element having a groove, rack means within said groove, and a clip adapted to be wedged within said groove to hold said rack means securely in position.

4. A printing plate supporting element having a groove, racks within said groove, a beveled recessed portion provided adjacent the bottom of said groove to receive said racks, and a plurality of clips adapted to be wedged between said racks to hold the latter securely within said recessed portion.

5. A printing plate supporting element having a groove with a curved base, racks within said groove, a beveled recessed portion provided adjacent the bottom of said groove to receive said racks, and a plurality of clips adapted to be wedged between said racks so as to assume the curvature of said base and hold said racks securely within said recessed portion.

6. In combination with printing plate securing means, a plate supporting base having a groove, rack means within said groove, and a plate hook adapted to be moved longitudinally of said groove and having a driven pinion with laterally projecting teeth of substantially cylindrical cross section to engage said rack means and advance said hook longitudinally of said groove, the diameter of the pitch circle of the teeth on said pinion being less than one-half of the diameter of the pinion.

7. In a printing plate securing means, the combination of a printing plate supporting

base, having a groove, rack means within said groove, a plate engaging hook including a driving element, and a driven element, having one or more rack engaging teeth extending from the side thereof to cooperate with said rack means for moving said hook longitudinally of said groove, the diameter of the pitch circle of the teeth on said driven element being less than one-half of the diameter of said element.

8. In printing plate securing means, the combination of a plate supporting base, a plurality of racks associated therewith, and a plate engaging hook including a rack engaging pinion having a laterally extending tooth at each side to mesh with said racks for moving said hook, one complete revolution of said pinion advancing said hook by one tooth of said racks.

9. In printing plate securing means, the combination of a plate supporting base, a plurality of racks associated therewith, and a plate engaging hook including a rack engaging pinion having oppositely extending teeth at each side to mesh with said racks for moving said hook, one complete revolution of said pinion advancing said hook by one tooth of said racks.

10. In printing plate securing means, the combination of a plate supporting base, a plurality of racks associated therewith, and a plate engaging hook including a rack engaging pinion having laterally extending teeth of substantially cylindrical shape to mesh with said racks for moving said hook, one complete revolution of said pinion advancing said hook by one tooth of said racks.

11. In printing plate securing means, the combination of a plate supporting base, a plurality of racks associated therewith, and a plate engaging hook including a rack engaging pinion having laterally extending teeth of substantially cylindrical shape arranged at each side to mesh with said racks for moving said hook, one complete revolution of said pinion advancing said hook by one tooth of said racks.

12. In printing plate securing means, the combination of a plate supporting base, a plurality of racks associated therewith, and a plate engaging hook including a rack engaging pinion having oppositely extending teeth of substantially cylindrical shape to mesh with said racks for moving said hook, one complete revolution of said pinion advancing said hook by one tooth of said racks.

13. In printing plate securing means, the combination of a plate supporting base, a rack associated therewith, and a plate engaging hook including a driven element having a tooth the base of which is located in a plane which extends at right angles to the axis of said element, said tooth being arranged to pass into said rack sidewise of the rack teeth,

thereby adapting it to remove foreign matter accumulated therebetween.

14. In printing plate securing means, the combination of a plate supporting base, a rack associated therewith, and a plate engaging hook including a driven element having a tooth of substantially cylindrical shape the base of which is located in a plane which extends at right angles to the axis of said element, said tooth being arranged to pass into said rack sidewise of the rack teeth, thereby adapting it to remove foreign matter accumulated therebetween.

15. In printing plate securing means, the combination of a plate supporting base, rack means associated therewith, and a plate engaging hook having a rack engaging pinion with teeth extending from each side thereof for moving said hook, the bases of said teeth being located in planes which extend at right angles to the axis of said pinion, and are arranged to pass into said rack means sidewise of the rack teeth, thereby adapting them to remove foreign matter accumulated therebetween.

16. In printing plate securing means, the combination of a plate supporting base having a groove provided with an under cut portion, rack means within said groove, a plate engaging hook operating within said groove, a rack engaging pinion, the diameter of the pitch circle of the teeth of which being less than one-half of the diameter of the pinion, and one or more retaining members resiliently mounted on said hook to engage said under cut portion and adapted to be forcibly compressed and expanded when said hook is within said groove.

17. A printing plate supporting element, having a groove, racks within said groove provided adjacent the bottom of said groove to receive said racks, and a plurality of clips adapted to be wedged between said racks to hold the latter securely within said groove.

18. In a printing plate securing means, the combination of a printing plate supporting base having a groove, rack means positioned within said groove and having teeth inwardly projecting from a side of the groove, a plate engaging hook mounted within said groove for longitudinal adjustment with respect thereto, said hook comprising a worm-shaped driving member rotatable about a vertical axis and a driven member arranged to be rotated through movement of said worm about an axis transverse to said groove, said driven element having teeth to engage with the teeth of said rack means.

19. In a printing plate securing means, the combination of a printing plate supporting base having a groove, a plate engaging hook detachably mounted in said groove and adapted for longitudinal adjustment with respect thereto, said plate hook comprising a worm shaped driving member rotatable

about a vertical axis, a driven element engaged by said worm and rotatable upon an axis transverse to said groove, teeth disposed on the ends of said driven member and rack teeth inwardly extending from the sides of said groove arranged to be engaged by the teeth of said driven member.

5
Signed at Chicago, Illinois, this 5th day of October, 1927.
